UNITED STATES PATENT OFFICE.

LEOPOLD THOMAS, OF HOBOKEN, NEW JERSEY, ASSIGNEE OF ONE-THIRD
TO JOHN A. DEKNATEL, OF BROOKLYN, NEW YORK.

LOW-WATER INDICATOR.

SPECIFICATION forming part of Letters Patent No. 237,929, dated February 15, 1881.

Application filed December 31, 1880. (No model.)

To all whom it may concern:

Be it known that I, LEOPOLD THOMAS, a citizen of the United States, residing at Hoboken, in the county of Hudson, and State of New Jersey, have invented new and useful Improvements in Low-Water Indicators for Steam-Boilers, of which the following is a specification.

This invention relates to devices for indicating the level of the water in steam-boilers; and it consists in the combination, with the steam-boiler, of a laterally-vibratory vessel having its upper end suspended from a fixed pivot, and its lower portion extending below and its upper portion above the water-line of the boiler, said portions being connected by flexible pipes with the water and steam spaces of the boiler, respectively, a scale-beam projecting laterally from said vessel, and a balance-weight arranged for adjustment upon said scale-beam, so that the swinging vessel may be counterbalanced in its perpendicular position when the water is at the proper level or height in the boiler, and when the water falls below such level the vessel is brought out of that position. An alarm or signal mechanism adapted to be operated by the movement of the swinging vessel shows its position.

This invention is illustrated in the accompanying drawings, in which Figure 1 represents a vertical central section. Fig. 2 is a front view.

Similar letters indicate corresponding parts.

The letter A designates the swinging vessel, B C its flexible connections with the boiler, and D the scale-beam.

The swinging vessel A is hung on a pivot, e, secured to the boiler or any other suitable support, and it is made steam and water tight. The flexible connections B C consist of pieces of india-rubber tubing, or they may be composed of jointed tubes of metal or other material, and the points at which the same are joined to the boiler are opposite to the water and steam spaces, respectively.

The scale-beam D is a fixture of the swinging vessel A, and carries a balance-weight, f.

It will be seen that both water and steam are admitted to the swinging vessel A from the boiler, and hence the level of the water is

the same in both. Now, when the water has arisen to the desired level the balance-weight f is set to counterbalance the swinging vessel A in the perpendicular position to which it is brought by the weight of the water therein, and when the water falls below such level the balance-weight overcomes the weight of the water and swings the vessel out of its position, thus indicating low water. A try-cock, H, is applied to the bottom of the swinging vessel.

In order to increase the effect of the swinging vessel A, I make use of an alarm mechanism which is adapted to be operated by the movement of the vessel. In this example this alarm mechanism consists of an electric switch, G, which is arranged in the path of the scale-beam D, so that the latter comes in contact therewith when the vessel A is swung out of a vertical position, thus closing a circuit for operating the alarm-bell; but this mechanism can be modified in various ways which will readily suggest themselves to a skilled mechanic.

What I claim as new, and desire to secure by Letters Patent, is—

1. The combination, with a steam-boiler, of a laterally-vibratory vessel having its upper end suspended from a fixed pivot and its lower portion extending below and its upper portion above the water-line of the boiler, said portions being connected by flexible pipes with the water and steam spaces, respectively, of the boiler, a scale-beam projecting laterally from the said vessel, and a balance-weight arranged for adjustment upon said scale-beam, substantially as described, and for the purpose set forth.

2. The combination, with the vessel A, suspended from a fixed point, and having its upper and lower portions respectively connected by flexible pipes with the steam and water spaces of the boiler, of the scale-beam D and alarm device C, substantially as described.

In testimony whereof I have hereunto set my hand and seal in the presence of two subscribing witnesses.

LEOPOLD THOMAS. [L. s.]
